UNITED STATES PATENT OFFICE.

HERBERT E. WILLIAMSON, OF SAN FRANCISCO, CALIFORNIA.

WASHING MACHINE.

Application filed March 31, 1926. Serial No. 98,762.

This invention relates to improvements in washing machines and has particular reference to a washing machine which may be employed with any form of tub either movable or stationary.

The principal object of this invention is to produce a device of this character which may be readily transported from place to place.

Another object is to produce a device which will wring the clothes, as well as functioning as a washer.

An additional object of this invention is to produce a device of this character which is simple in construction and, therefore, one which will not be easily disarranged.

A still further object of this invention is to produce a device which will be cheap to manufacture, and at the same time neat in appearance, easy to operate and silent in operation.

A further object is to provide suitable means for mechanically moving the wringer post to any desired position without releasing the post.

Other objects and advantages will be apparent during the course of the following description.

In the accompanying drawings forming a part of this specification, and in which like numerals are employed to designate like parts throughout the same,

Figure 1 is an enlarged side elevation of my device partly broken away in order to better illustrate my invention,

Figure 2 is a cross section taken on the line 4—4 of Figure 1,

Figure 3 is a horizontal cross section taken on the line 3—3 of Figure 4,

Figure 4 is a vertical cross section of the gearing arrangement,

Figure 5 is a side elevation of the gearing arrangement taken on the line 5—5 of Figure 4 and showing the wringer gearing associated therewith,

Figure 6 is a vertical cross section of the wringer and its gearing,

Figure 7 is a fragmentary detail view showing the manner of supporting the driving motor,

Figure 8 is a fragmentary detail view showing the manner of connecting the wringer shaft to the wringer driving gear,

Figure 9 is a cross section of the wringer supporting housing, and

Figure 10 is a detail view showing the

manner of rotating the wringer supporting housing.

There are many instances where it is desired to employ the customary wash tubs by using a mechanical scrubbing element, thereby eliminating the necessity of discarding the washing apparatus which is on hand. I have, therefore, perfected a portable device comprising a motor, a gearing arrangement, a wringer and a washing element so arranged that they may be rolled as a unit into close proximity to the wash tubs, after which the motor is started and the washing and wringing operation is completed.

In the accompanying drawings wherein for the purpose of illustration is shown a preferred embodiment of my invention, the numeral 5 designates a suitable casing having legs 6 and casters 7.

Positioned within the casing 5 is a suitable support 8 which carries a pivoted member 9. This pivoted member 9 has positioned thereon a gear 11 which carries a crank 12 to which a crank pin 13 is secured. A pitman 14 is secured to the crank 12 and has its upper end pivotally secured to a reciprocating rod 16. This rod 16 is provided with a head 17 on which is secured a cross arm 18, to the end of which is adjustably secured as by a slider 19, a washer head 21 having cups 22 secured thereto.

These cups are of the usual washer cup construction and need no further description. A cam 23 is adapted to underlie a nose 24 of the pivoted member 9 serving to maintain the gear 11 in mesh with a gear 26 which is secured upon a shaft 27.

This shaft 27 has, in turn, a pulley 28 secured thereto. Over this pulley is reaved a belt 29 which belt, in turn, passes over a pulley 31 secured to the motor shaft 32 of the motor 33. This motor is secured to a bracket 34 as best shown in Figures 2 and 7, while the bracket is, in turn, pivoted as at 36 and resiliently held against pivotal movement by a bolt 37 passing through an L-shaped arm 38.

This bolt carries a spring 39 which bears against one end of the L-shaped arm and has its opposite end bearing against a nut 41 secured upon the bolt 37. The gear 26 has a bevel gear 42 formed thereon which, in turn, meshes with a bevel gear 43 positioned within the housing 44.

A stub shaft 46 extends through the hous-

ing 44 and is keyed to the gear 43 and is provided with a pin 47 on its upper extremity. This pin is adapted to fit in a slot 48 formed in a collar 49 secured to the lower extremity 5 of the wringer driving shaft 51. This wringer drive shaft is enclosed in a wringer supporting housing 52, which housing is, in turn, supported by the housing 44.

This wringer supporting housing 52 passes up through the main housing 5 and has a gear 53 secured thereto, which gear is, in turn, engaged by a worm 54 rotatable by a handle 56. This arrangement permits the housing 52 to be rotated so as to swing the 15 wringer head into any desired position.

This wringer head is designated as a whole by the numeral 57; and within the same is positioned wringer rollers 58 and 59. The roller 59 is rotated by a gear 61 which 20 meshes with bevel gears 62 and 63. These gears 62 and 63 are provided with ratchets as shown at 64 and 66, respectively, and are adapted to be engaged individually by a clutch 67 operated by a handle 68. This 25 clutch mechanism is common practice and, therefore, needs no further comment.

It will thus be seen that when the motor 33 is rotated, due to the power being turned on, motion will be transmitted to the belt 29, to pulley 28. This motion will, in turn, be transmitted through the shaft 27 and gear 42, through the gear 43, thence through stub shaft 46 to shaft 51 upon which the clutch 67 is keyed.

By now moving the clutch 67 into engagement with either of the ratchets on each of the gears 62 or 63 motion may be imparted to the wringer rollers 59 and 58. If the cam 23 is positioned so as to raise the member 9 and 40 bring the gear 11 into engagement with the gear 26 motion will be transmitted to this gear and through its crank connection to the reciprocating rod 16. This will cause the

arm 18 and its attached parts to be reciprocated up and down which will perform the 45 washing operation.

Should it be desired to swing the wringer into any desired position, this may be accomplished by rotating the handle 56.

It will thus be seen that I have produced a 50 wringer of the character described, which will perform all of the advantages above set forth.

It is to be understood that the form of my invention herewith shown and described is 55 to be taken as a preferred example of the same, and that various changes in the shape, size and arrangement of parts may be resorted to without departing from the spirit of the invention or the scope of the subjoined claim.

Having thus described my invention, I claim:—

In a washing machine of the character described, a portable casting, a motor resiliently supported in said casting, a gear mechanism supported within said casting and adapted to be driven by said motor, said gear mechanism comprising a shaft, a gear mounted on said shaft, a pivoted member supported below said gear, a second gear mounted on said pivoted member, means for raising said second mentioned gear into contact with said first mentioned gear, a crank secured to said second mentioned gear, a pitman secured to said crank, a reciprocating rod secured to said pitman and adapted to be actuated thereby, a bevel gear positioned on said shaft and having a second bevel gear in constant mesh therewith, said second mentioned bevel gear being adapted to drive a vertically disposed shaft for the purpose specified.

In testimony whereof I affix my signature.

HERBERT E. WILLIAMSON.
